(57) **CLAIM**

The ornamental design for trigger for compact defeater handle, as shown and described.

DESCRIPTION

FIG. 1 is bottom right perspective view of the trigger for compact defeater handle of my new design, showing the trigger in the environment of the compact defeater handle. FIG. 2 is a bottom right side perspective view of the trigger of FIG. 1.

FIG. 3 is rear view of the trigger of FIG. 1.

FIG. 4 is front view of the trigger of FIG. 1.

FIG. 5 is a right side view of the trigger of FIG. 1, with the left side view being a mirror image of FIG. 5.

FIG. 6 is a top view of the trigger of FIG. 1; and, FIG. 7 is a bottom view of the trigger of FIG. 1.

The dot dash dot lines immediately adjacent to the shaded areas represent bounds of the claimed design. The broken lines of the trigger for compact defeater handle directed to unclaimed features and form no part of the claimed design.
